Fig. 2.

UNITED STATES PATENT OFFICE.

EWALD HERMSDORF, OF BRUNSWICK, GERMANY.

SYSTEM FOR ELECTRICALLY TRANSMITTING SIGNALS.

1,035,009.

Specification of Letters Patent.

Patented Aug. 6, 1912.

Application filed October 10, 1911. Serial No. 653,809.

To all whom it may concern:

Be it known that I, EWALD HERMSDORF, director, subject of the Duchy of Brunswick, Empire of Germany, residing at 35 Elmstrasse, Brunswick, Germany, have invented certain new and useful Improvements in Systems for Electrically Transmitting Signals, of which the following is a specification.

10 My invention relates to improvements in systems for electrically transmitting signals from or to movable bodies, and more particularly to signaling apparatus for trains, elevators, hoisting machines such as overhead traveling cars, trolley cars, etc. Apparatus of this class such as are now in use are unsatisfactory in operation, because the contact between the movable and stationary parts can not be made in a simple and reliable way.

The object of my improvements is to provide a system in which the difficulty of providing a reliable contact is avoided.

With this object in view my invention 25 consists in providing the connection between the relatively movable parts over a spark gap which is adapted to be traversed by currents of high voltage.

For the purpose of explaining the invention 30 several examples embodying the same have been shown in the accompanying drawings, in which the same letters of reference have been used in all the views to indicate corresponding parts.

35 In said drawings—Figure 1, is a front view of a locomotive and a diagrammatical view of apparatus for providing high voltage currents, a spark gap over which the locomotive and the said apparatus are connected, and a signaling device, Fig. 2, is a 40 partial side view of a locomotive showing a modified form of the pole carried by the locomotive for the spark gap to increase the duration of the signal and Figs. 3 and 4, are 45 diagrammatical views of further modifications of the signaling system.

Referring more particularly to the drawings the signaling system consists of an electric circuit which includes an apparatus 50 a for producing an electric current of high voltage, such for example as an induction coil, a condenser, Leyden jars, or the like, an indicating apparatus F , and one or more spark gaps consisting of a pole or poles carried by each of the relatively movable parts, and electric conductors b and b^1 .

In the example shown in Fig. 1 the apparatus a for producing current of high voltage, the indicating apparatus F , and the pole b^3 are mounted on the stationary part, 60 that is on or adjacent to the track, while the pole b^4 is provided on the movable part, that is on the locomotive c , and in such a position as to pass along and in close proximity to but out of contact with the pole b^3 . 65 Over the conductor b^1 and the metallic parts of the locomotive c , and the wheels g , the circuit is connected to ground at the point x and at the rails respectively. Therefore, when the locomotive passes with its pole b^4 70 along the pole b^3 the circuit is closed over the ground at x , the conductor b^1 , the apparatus a , the conductor b , the signaling apparatus F , the spark gap b^3 , b^4 , the locomotive c , the wheels g , and the rails h , so 75 that an electric discharge takes place between the poles b^3 , b^4 .

The signaling apparatus F is constructed in such a way as to be operated by electric discharges of the character referred to. In the example shown it consists of a spark gap arranged to act on a coherer z which energizes a galvanometer e or relays. The coherer energizes the relays or galvanometer e whenever the pole b^4 is brought in position to permit an electric discharge between the poles b^3 and b^4 . 85

If it is desired to increase the duration of the electric discharge over the poles b^3 and b^4 , and thereby the duration of the signal, 90 either both of the poles or one of them may be elongated in the direction of the travel of the vehicle.

In the modification shown in Fig. 2 the pile b^{14} which is mounted on the locomotive 95 is constructed in the form of a rail.

In Fig. 3 I have shown an example in which the circuit provided on the stationary part is provided with two poles b^5 and b^6 , while the movable part carries a bridge piece 100 b^{24} which is adapted to form two spark gaps with the poles b^5 and b^6 . The said bridge piece may also be divided into two sections b^7 and b^8 , as is shown in Fig. 4. Between the sections b^7 and b^8 a second signaling apparatus D may be interposed. Thereby a signal may also be produced on the movable part or locomotive c . Instead of the galvanometer e an acoustic or optical signaling apparatus may be provided. 110

I claim herein as my invention:

1. In a system for electrically transmit-

ting signals between relatively movable parts, the combination with a source of high potential energy, of a signaling apparatus, a pole on each of said parts, said poles being disposed in position to pass each other in close proximity but without contact, and electrical connections including said source of high potential energy, signaling apparatus and poles into a circuit which is adapted to be closed by said poles when in close proximity to each other.

2. In a system for electrically transmitting signals between relatively movable parts, the combination with a source of high potential energy, of a signaling apparatus, a pair of poles provided on one of said parts, a bridging pole provided on the other one of said parts and disposed in position to pass said pair of poles in close proximity thereto but out of contact therewith and to bridge the said pair of poles, and electrical connections including said source of electric energy, signaling apparatus and pair of poles into a circuit which is normally open at said pair of poles and adapted to be closed by said bridging pole.

3. In a system for electrically transmitting signals between relatively movable parts, the combination with a source of high potential energy, of a main signaling apparatus, a pair of poles provided on one of said parts, a bridging pole comprising two sections and provided on the other one of said parts and disposed in position to pass said pair of poles in close proximity thereto but out of contact therewith, and to bridge the said pair of poles, a subsidiary signaling apparatus connected to both of said sections of the bridging pole, and electrical connections including said source of electric energy, main signaling apparatus and a pair

of poles into a circuit which is normally open at said pair of poles and adapted to be closed by said bridging pole.

4. In a system for electrically transmitting signals between relatively movable parts, the combination with a source of high potential energy, of a pair of poles provided on one of said parts, a bridging pole comprising two sections and provided on the other one of said parts and disposed in position to pass said pair of poles in close proximity thereto but out of contact therewith and to bridge the said pair of poles, a signaling apparatus connected to both of said sections of the bridging pole, and electrical connections including said source of electric energy, and pair of poles into a circuit which is normally open at said pair of poles and adapted to be closed by said bridging pole.

5. In a system for electrically transmitting signals between relatively movable parts, the combination with a source of high potential energy, of a signaling apparatus comprising a spark gap, a coherer energized by said spark gap, and indicating means controlled by said coherer, a pole on each of said parts, said poles being disposed in position to pass each other in close proximity but without contact, and electrical connections including said source of high potential energy, signaling apparatus and poles into a circuit which is adapted to be closed by said poles when in close proximity to each other.

In testimony whereof I have hereunto set my hand in presence of two subscribing witnesses.

EWALD HERMSDORF.
